PAIR OF SPECTACLES OR THE LIKE

Gordon A. Brown, Pomfret Center, Conn., assignor to American Optical Company, Southbridge, Mass., a voluntary association of Massachusetts

Application October 4, 1949, Serial No. 5,293

Term of patent 14 years

(Cl. D57—1)

To all whom it may concern:

Be it known that I, Gordon A. Brown, a citizen of the United States of America, residing at Pomfret Center, in the county of Windham and State of Connecticut, have invented a new, original, and ornamental Design for a Pair of Spectacles or the like, of which the following is a specification, reference being made to the accompanying drawings, forming a part thereof.

Fig. 1 is a front elevational view of a pair of spectacles or the like embodying my new design.

Fig. 2 is a top plan view of a pair of spectacles or the like shown in Fig. 1; and

Fig. 3 is a side elevational view thereof.

The characteristic features of my new design are shown in full lines in the drawing.

I claim:

The ornamental design for a pair of spectacles or the like, substantially as shown and described.

GORDON A. BROWN.
